UNITED STATES PATENT OFFICE.

EDWARD B. SINKLER, OF NEW YORK, N. Y.

VALVE-STEM CASE.

No. 897,936.

Specification of Letters Patent. Patented Sept. 8, 1908.

Application filed October 1, 1907. Serial No. 395,350.

To all whom it may concern:

Be it known that I, EDWARD B. SINKLER, of the city of New York, borough of Brooklyn, county of Kings, State of New York, 5 have invented certain new and useful Improvements in Valve-Stem Cases, of which the following is a full, clear, and exact specification, such as will enable others skilled in the art to which it appertains to make and

10 use the same.

My invention relates particularly to the valve stems and actuating devices of internal combustion engines such for example as the typical gasoline engine employed in automobile work. In such engines it is a well known disadvantage that dust and grit attach themselves to the valve stem and its actuating device with the result that the guides are cut and the parts become loose. 15 From this condition lost motion arises thus destroying the proper timing of the valves. Further, as the guides are cut the tight fit of the stem in the stem guide is destroyed and thus the effect of the suction stroke of the 20 piston is impaired with the result that the charges are not properly drawn into the engine.

The object of my invention is to overcome this disadvantage and I attain this result by 25 means of a peculiarly constructed case which incloses the valve stem and its actuating pin or rod and which is held in place by the spring that serves also to seat the valve which spring is thereby caused to perform a double 30 function. This case tightly incloses all of the moving parts and effectually excludes the entrance of dust and other gritty substances. It also serves as a means for holding a lubricant and directs this lubricant from 35 the valve stem and its actuating device into the crank case of the engine where the lubricant is again utilized, effecting a decided economy in this respect.

The invention is applicable both to the admission and exhaust valves of the engine and is particularly useful on the admission valve.

The invention involves various other features of importance, and all will be fully set forth hereinafter and particularly pointed 40 out in the claims.

Reference is had to the accompanying drawings, which illustrate as an example, one manner of embodying my invention, in which drawings,

45 Figure 1 is a vertical section showing the invention; Fig. 2 is a reduced side elevation

of the case; and Fig. 3 is an enlarged horizontal section on the line 3—3 of Fig. 2.

a indicates the stem of the valve which stem is of that construction usually incident to the puppet or similar valves of gas engines. The stem passes through the usual guide *b* and into the combustion space of the engine as will be understood from the prior art.

c indicates a fragment of the usual cam for actuating the valve which engages a roller *d* held in the fork *e'* of the stem operating pin or rod *e*. This is provided with the usual adjustable cap *e*² which is adapted to engage 70 the stem *a* and by the adjustment of which the proper operation of the valve may be secured. This actuating rod *e* is held in a guide *f'* which is fastened to the case inclosing the cam shaft of the engine. A fragment 75 of this case is indicated at *f* in the drawings. All of these parts may be of the usual or any desired construction.

h indicates my improved case which is preferably constructed of aluminium castings though it may of course be of other materials. It is made by preference in two sections as indicated in Fig. 3 and these sections are, removably held together by means of swing bolts *h'* pivoted on and engaging lugs 80 *h*² formed on or fastened to the casting. By these devices, the castings may be quickly engaged and disengaged. For the purpose of effecting a tight joint between these sections, I provide a gasket *h*³ of felt or the like 85 which is let into the edges of one section to engage the adjacent edges of the other section. The case is also provided with a plug *h'* or other device facilitating the introduction of oil as will be fully set forth hereinafter. 90 This case incloses the exposed parts of the valve stem and its actuating rod and extends from the stem guide *b* to the rod guide *f'*.

i indicates the usual spring which is connected with the valve stem to seat the valve. This spring is also inclosed by the case and engages the inner side of its upper end. A felt or other gasket *g* is interposed between the upper end of the case and a shoulder *b'* 105 on the stem guide *b* to make a tight joint. The spring, it will be perceived, in addition to performing its usual functions in seating the valve, serves also to hold the case in position, pressing it firmly against the gasket *g* 110 and shoulder *b'*. At its lower end the case is contracted to meet the upper end of the

guide f' and at this point is provided with the gasket of felt or other material h^s which is let into the edge of the case and engages the guide j' to form a firm connection. It will thus appear that the case completely incloses all of the moving parts concerned with the valve stem and that it is sustained firmly by the spring i , the lower end of the case inclosing the guide j' but not necessarily sustained by it. This case, it will be seen, fully protects all of the parts from dust, dirt and other accumulations tending to cut and wear the parts and it, therefore, prevents them from wearing and becoming inaccurate in action. It also enables me to fully lubricate the parts by filling or partly filling the case with oil. This oil is retained by the gasket h^s and will eventually find its way between the stem f' and rod e into the crank case of the engine, where it will be further utilized by lubricating the cams and the cam shaft.

Having thus described my invention, what I claim as new and desire to secure by Letters Patent of the United States is:—

25 1. The combination with an engine having a valve stem and an actuating device therefor, of a case extending between relatively stationary parts of the engine and inclosing

the exposed portions of the valve stem and actuating device, and a spring engaging the valve stem to seat the valve and also engaging the case to hold it in place.

2. The combination with an engine having a valve stem and an actuating device therefor, of a case extending between relatively stationary parts of the engine and inclosing the exposed portions of the valve stem and actuating device, said case being formed into two longitudinal sections and having means for removably holding them together, whereby the case may be applied to and removed from position.

3. The combination in an internal combustion engine of a valve stem a guide for the stem a case inclosing the exposed portion of the stem and extending from the guide, and a spring engaging the valve stem to actuate it and also engaging the case to hold it in position.

In testimony whereof I have signed my name to this specification in the presence of two subscribing witnesses.

EDWARD B. SINKLER.
